UNITED STATES PATENT OFFICE.

HUGH J. SULLIVAN, OF MILWAUKEE, WISCONSIN.

SKYLIGHT-FRAME.

SPECIFICATION forming part of Letters Patent No. 334,487, dated January 19, 1886.

Application filed August 3, 1885. Serial No. 173,310. (No model.)

To all whom it may concern:

Be it known that I, HUGH J. SULLIVAN, of Milwaukee, in the county of Milwaukee and State of Wisconsin, have invented new and 5 useful Improvements in Skylight-Frames; and I do hereby declare the following to be a full, clear, and exact description of said invention, reference being had to the accompanying drawings, and to the letters or figures of reference 10 marked thereon, which form a part of this specification.

My invention, to be hereinafter distinctly claimed, is illustrated in the drawings, as follows:

15 Figure 1 is a perspective of a section of a raised skylight in which my improved frame is shown. Fig. 2 is a detail.

A is the principal frame or curb on which the skylight is supported, the top of which is beveled off downwardly outwardly to correspond 20 with the angle of the skylight. The outside and top of this curb A are partly or wholly covered with tin or sheet metal e. Over this curb is placed a covering, B, formed out of a single 25 piece of sheet metal, and so constructed as to provide a glass-supporting shoulder upon and directly above the curb, and a gutter on the inside of the curb below the ends of the central parts of the frame, for conveying away the 30 water of condensation from the under side of the glass. A sheet of metal is folded upon itself at f, forming two leaves. These leaves are bent at an acute angle to form a gutter at g, and are again bent reversely at h over the top 35 of the curb, the curb being preferably beveled off downwardly outwardly on its top. A little way down from the angle h, on the top of the curb, the outer leaf of the covering B is bent out at right angles, forming a shoulder, 40 i, for the support of the glass, and the leaf is then bent downwardly again at an angle to the other leaf, where this outer leaf terminates, and the edge is received into and held by a fold, j, made in the inner leaf for that purpose, and 45 the inner leaf is continued down over the outside of the curb, forming an outer covering, k, terminating in an outwardly-projecting lip for carrying the water flowing over it away from the curb. The central supporting-bars, C, of 50 the skylight-frame are each made from one piece of sheet metal, which is folded together

at l, both leaves at a distance from the fold l being bent outwardly at right angles, forming the shoulders m m, then converging inwardly downwardly therefrom to n, where they are 55 again both bent outwardly and backwardly, forming gutters o o, and one of the leaves p is folded back upon itself and around over the edge of the other leaf at q, forming strong gutters, and holding the lower part of the two 60 leaves firmly together at n. The lower ends of the bars C are made rigid to the covering B, the gutters o o are run into the gutter g, and the shoulders m m are continuous and on the same plane with the top of the curb A. The 65 glass r of the skylight rests upon the shoulders m m and on the beveled top of the curb A, its lower edge resting against and being supported by the shoulder i. The glass is bedded in putty s. That part of the bar C from 70 which the shoulders m m project, and which extends between the panes of glass, projects outwardly beyond the glass, forming a wing-standard, t, which supports the cover D. The cover D is formed of a single piece of sheet 75 metal bent downwardly, forming a ridge, u, then inwardly, forming the shoulders v v, and terminating in outwardly-extending lips adapted to fit upon and press against the upper surface of the glass. The standard t is provided with lugs w w, projecting at right angles 80 therefrom, formed by cutting slits downwardly from the top into the standard and bending over alternately to right and left the tongues w w. These lugs w w are located and adapted 85 to permit the shoulders v v to pass just beneath them, when the cover D is slid on over the standard t, whereby the cover is held down firmly on the standard t, the lower edges of the cover being tight down on the glass. The 90 ridge-bar of the frame is constructed similarly to the central bars, C.

To carry off the water from the gutters g g, a trough or pipe, x, is run from the gutter g outwardly through the curb A, terminating, 95 preferably, at the outside of the covering e, and within the covering k, which latter covering forms a cap over the outer end of the pipe x, closing it, except to the outflowing drip from the gutter. The pipe x can be put in through 100 an aperture through or a socket in the curb A, as is most convenient or desired.

What I claim as new, and desire to secure by Letters Patent, is—

1. In skylight-frames, the wing-standard *t*, extending above the glass of the skylight, and the lugs *w w*, rigid on the standard *t*, in combination with the cover *D*, provided with shoulders *v v*, substantially as and for the purpose set forth.
2. In skylight-frames, the sheet-metal curb-covering *B*, provided on its upper outer surface, directly above and upon the top of the curb *A*, with a glass-supporting shoulder, *i*, substantially as described.
3. In skylight-frames, the sheet-metal curb-covering *B*, provided on its inner side with a gutter, *g*, in combination with the pipe *x*, leading from the gutter *g* to the outside of the curb *A*, substantially as described.
4. The sheet-metal curb-covering *B*, provided on its upper outside surface with a glass-supporting shoulder, *i*, in combination with

one or more central bars, *C*, provided with standards *t*, having lugs *w w*, the glass *r*, and the cover *D*, provided with shoulders *v v*, all substantially as described.

5. In skylight-frames, a central supporting-bar, *C*, constructed of a single piece of sheet metal folded together at *l*, provided with the shoulders *m m* and the gutters *o o*, said gutters being formed by the two leaves of the sheet metal being bent outwardly and backwardly, and the leaf on one side being folded backwardly upon itself on the outside and around over the edge of the other leaf at *q*, substantially as described.

In testimony whereof I affix my signature in presence of two witnesses.

HUGH J. SULLIVAN.
